STORING AND DISPENSING

Albert Waddell, Detroit, Mich.

Application March 15, 1937, Serial No. 130,860

2 Claims. (Cl. 34—24)

This invention relates to a cabinet especially designed for use in storing potato chips and from which the chips may be dispensed.

The cabinet or case may be so constructed as to display the contents, and is particularly useful in such places as restaurants, so-called beer gardens, way-side inns and such places, particularly where light wines and beers are consumed. The potato chip, in its proper form, is an excellent serving with beer. However, potato chips must be very carefully handled in order that the chips are in the most desirable state when served. The chips must have a crispness and freshness. If moisture gets into the chips they become soggy and undesirable with the result that they are unsold. On the other hand, care must be taken, if an attempt is made to drive off the moisture by heat, else the oils or fats involved will penetrate into the body of the chips and they are again rendered soggy or soft.

This invention is directed toward the provision of a cabinet, for storing potato chips and from which they may be dispensed, for maintaining the crispness and freshness of the chips and for keeping them at a high point of perfection. In this connection the cabinet is heated. However, mere heating is not sufficient because if the body of air in the cabinet is stagnant the freshness is lost and the chips may become moist by penetration of oil or moisture, or both. Therefore, the cabinet is not only heated, but fully ventilated so that there is a movement of current of air through the cabinet and chips therein. This air, being heated, has a drying action so that moisture is not only prevented from getting to the chips but may be extracted therefrom. The heating of the cabinet, however, must be kept within limits because too high a heat will cause the oil to penetrate and cause the chips to become soft and undesirable. According to the invention a cabinet is provided by which the chips are kept heated and ventilated so that they are maintained in a warm crisp condition free from moisture and yet with the temperature which does not cause the oil or fats to penetrate, thus substantially maintaining the original crispness and freshness of the chips.

In the accompanying drawings:

Fig. 1 is a perspective view of a cabinet constructed in accordance with the invention.

Fig. 2 is a rear elevation of the cabinet.

Fig. 3 is a sectional view substantially on line 3—3 of Fig. 2.

Fig. 4 is a sectional view substantially on line 4—4 of Fig. 3.

Fig. 5 is a detail view in section taken substantially on line 5—5 of Fig. 3.

The cabinet which is illustrated in the drawings for carrying out the invention is of rectangular form having a post 1 at each corner and horizontal end and side rails 2, thus forming a frame structure. Three vertical sides may be enclosed by a panel such as glass, as illustrated at 3, 4 and 5. The top of the case may be provided by a panel which may be glass, as illustrated at 6. In order to ventilate the case at the top, the top panel may rest upon studs 7, thus leaving a ventilating space 8 extending substantially entirely around the top of the cabinet.

The back of the cabinet, or the side nearest the operator or user, may be closed by opaque closure elements such as wood or sheet metal. As shown in Fig. 2 the upper portion is closed by a panel 10, the lower portion by a panel 11 hinged as at 12 so that it can be opened and which may be held closed by a suitable latch 13. The interior of the cabinet may be equipped with a suitable guard or shield comprising a downwardly inclined top shield 15 overhanging side shields 16. Thus a body of chips which may be in the cabinet (visualizing Fig. 3) will not fall out of the opening when the door 11 is opened and the operator may, by the use of a suitable scoop, obtain such quantity of contents as he desires.

The bottom of the cabinet for supporting the chips preferably takes the form of a screen 20. This screen may be of desired suitable mesh, and while the same supports the chips it allows air to enter freely. Underneath the screen is a heating element, preferably an electrical resistance wire. This is illustrated at 21 and may be mounted upon a suitable support or frame as indicated at 22. Of course, the heating element may take any one of numerous forms. Electrical conductors 23 may extend to a suitable plug 24 for connection to an electrical power line. Also, underneath the screen 20 is a tray 25 which may be slidably received on rails 26. This tray is for the purpose of catching small pieces which fall through the screen. It may be removed from time to time and cleaned.

This case may be filled or substantially filled with chips. The heating element is preferably arranged to maintain a heat on the chips of about 110° F. Due to the full ventilation of the cabinet, convection currents pass upwardly through the cabinet at all times so that the air is fresh and the chips maintained warm and crisp, and yet the temperature does not exceed that tempera-

ture at which the oils or fats would be driven into the body of the chips.

I claim:

- 5 1. The method of storing potato chips in bulk and from which quantities thereof may be dis-
pensed from time to time, for preserving the crisp-
ness and freshness of the chips which com-
prises, placing a bulk quantity of chips in a con-
tainer having lower and upper portions for the
passage of air therethrough, heating the air and
10 chips from below whereby to cause convection
currents to flow through the bulk quantity of
chips and through the container to maintain the
chips in a dry, warm, crisp condition and main-
taining a temperature on the chips sufficiently
15 high to keep the chips fresh and crisp and sub-
stantially free of moisture and which temperature
is below that at which the chips would be ren-

dered soggy by the driving of the oils or fats into
the body of the chips.

2. The method of storing potato chips in bulk
and from which quantities thereof may be dis-
pensed from time to time for preserving the crisp-
ness and freshness of the chips which comprises,
5 placing a bulk quantity of chips in a container
having lower and upper portions for the passage
of air therethrough, heating the air and chips
from below whereby to cause convection currents
to flow through the bulk quantity of chips and
10 through the container to maintain the chips in
a dry, warm, crisp condition and maintaining a
temperature on the chips of about 110° F. to keep
the chips fresh and crisp and substantially free
15 of moisture without driving the oils or fats into
the body of the chips.

ALBERT WADDELL.
